Primary Examiner — Michael C Stout*Assistant Examiner* — Emmett Cygnet(74) Attorney, Agent, or Firm — Daniel M. Cohn; Howard M. Cohn(57) CLAIM

The ornamental design for a wax heater for hair removal as shown and described.

DESCRIPTION

FIG. 1 is a perspective view of a wax heater for hair removal showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the wax heater for hair removal that form no part of the claimed design.
